UNITED STATES PATENT OFFICE.

FRANK B. MCGRANE, OF SOMERVILLE, MASSACHUSETTS.

COMBINATION ROAD-VEHICLE.

1,316,373.

Specification of Letters Patent. Patented Sept. 16, 1919.

Application filed August 11, 1917. Serial No. 185,716.

To all whom it may concern:

Be it known that I, FRANK B. MCGRANE, a citizen of the United States, and a resident of Somerville, in the county of Middlesex and State of Massachusetts, have invented an Improvement in Combination Road-Vehicles, of which the following description, in connection with the accompanying drawings, in a specification, like characters 10 on the drawings representing like parts.

This invention relates to a power operated vehicle for performing work on roads, highways and like places, and has for its object to provide such a vehicle with means 15 as will be described, whereby the said vehicle may be capable of performing a variety of additional kinds of work, which imparts to the said vehicle the function of a general utility machine, with which different kinds of work may be performed at a 20 minimum expense.

The invention is especially adapted to be embodied in power operated vehicles of the road roller or tractor type, which are now 25 provided with sufficient motive power to not only propel the vehicle over the road but to perform the additional work for which they are assigned.

To this end, the power operated road vehicle is provided with a boom for carrying a tool, such as a scoop or bucket and which will be hereinafter referred to as a bucket, and said boom has mounted on it a device for lifting the boom, which device is 30 capable of being moved lengthwise on the boom and of being rendered stationary on said boom in any desired position, and to which the bucket may be connected by a cable of other flexible connection, so that the same bucket may be used for different kinds 35 of work, as for instance, for surface and trench work, as will be described.

The device which is capable of being moved longitudinally on the boom, may for 40 sake of clearness be designated a carriage, and when the machine is to be used for trench work, the bucket is connected with said carriage to be moved therewith in one direction, and said bucket has also connected 45 with it a cable or line for moving it and the carriage in the opposite direction.

When the machine is to be used for surface work, the carriage is rendered stationary on the boom in any selected or desired

position, and provision made for moving the 55 bucket independently of the carriage.

The boom is pivoted to a support or carrier, which is vertically movable so that, the boom and bucket may be positioned with relation to the surface of the ground to enable the machine to do different kinds of work as will be described. The carrier for the boom is vertically movable on a mast, which is capable of being moved from a vertical position into inclined positions for a 60 purpose as will be described, and said mast is carried by a frame which is mounted on a rotatable vertically arranged shaft having its bearings supported by the body portion of the vehicle, whereby not only is a solid 65 support provided but also one which conveys the thrust put upon the frame directly to the body of the vehicle. Provision is made for automatically locking the bucket to the boom, when the bucket is in its dumping or discharging position, which permits a rigid bucket to be used and avoids the necessity of a separate line or cable for dumping the bucket, which in some cases requires an extra man for working it.

These and other features of this invention will be pointed out in the claims at the end of this specification.

Figure 1 is a side elevation of a sufficient portion of a motor operated road vehicle 85 embodying this invention to enable it to be understood.

Fig. 2, a diagrammatic view of the front portion of the machine shown in Fig. 1, to illustrate its use for ordinary excavating 90 purposes.

Figs. 3, 4 and 5, like views showing the use for various angles of trench work.

Fig. 6, a like view showing the use of the bucket for hoisting purposes.

Fig. 7, a like view showing the use of a different bucket.

Fig. 8, a like view showing use of the bucket for surface work.

Fig. 9, a plan view of a portion of the 100 machine shown in Fig. 1.

Fig. 10, a detail to illustrate the winding drum.

Fig. 11, a detail of the transmission preferred by me.

Fig. 12, an enlarged section of the boom, the section being taken on the line 12-12, Fig. 1.

Fig. 13, a detail in side elevation of the automatic lock to be referred to, and

Fig. 14, a detail of the mechanism for rotating the mast carrying frame.

5 In the present instance, I have illustrated the invention as embodied in a power driven road vehicle *a* of the tractor type, which is of known construction and is represented as a steam operated vehicle provided with a
10 body portion *b*, supported by the rear wheels *c* and front wheels *d*, the latter being pivotally mounted to permit the vehicle to be guided over the road.

15 The tractor *a* is provided with a suitable motor or engine *e* for propelling it over the road and for performing one kind of work, and the particular type herein illustrated is designed for hauling material over the road.

20 The tractor *a* in accordance with this invention is provided with mechanism for performing work of a different character, and in the present instance, the tractor is shown in Fig. 1 as provided with mechanism which is capable of working on or above the surface of the road and, with slight changes, of working below the surface of the road.

25 Referring to Fig. 1, 10 represents a boom, preferably made of two channel irons spaced apart and suitably secured together, (see Fig. 12). The boom 10 is provided with a track or guide 14 for a carriage or device 15, which is movable lengthwise of the boom on said track or guide, and is capable of being rendered fixed or stationary at any desired portion of the length of the boom or is capable of being freely movable lengthwise on said boom according to the kind of work to be performed, as will be described.

30 As shown in Fig. 1, the carriage 15 is stationary, being secured to the track or guide 14 by a pin 16. The boom 10 is pivoted at its inner end as at 17 to a carrier 18, which is movable lengthwise of a mast or support 19 normally vertically arranged.

35 45 The mast 19 is secured to a supporting frame, preferably made as herein shown and comprising bars or arms 20, 21, which are connected by a tie plate or bar 22.

40 50 In the present instance, the mast 19 is pivoted at its lower end as at 23 to the arm 20, and its upper end is secured to the arm 21, when the mast is to have a vertical position, and may and preferably will be adjustably secured to a curved extension 24 of the
55 arm 21, when it is desired to have the mast given different inclined positions. The curved extension 24 is preferably pivotally secured to the arm 21 by a hinge 25 or otherwise, which permits the extension to be
60 folded or turned back so as to rest on the arm 21 when not in use. The extension 24 may be provided with suitable holes 26 spaced apart to enable the upper end of the mast to be secured in fixed relation to the
65 extension by a suitable pin 27, and thereby

render the mast stationary in different inclined positions. The extension 24 is made in a curve having the pivot 23 as a center, and is also preferably made as a channel bar, and the mast 19 is preferably provided with a roller 28, which is movable in the channel of the extension, and to avoid the necessity of machining the channel bar extension, the mast 19 is provided with a movable upper member 30, which carries the roller 28 and is acted upon by a spring 31 to hold the roller 28 in engagement with the upper or outer flange of the channel bar. The arms 20, 21 of the supporting frame are provided with collars or eyes 32, 33, through which are passed a rotatable shaft 34 having a bearing in a sleeve 35, which is mounted in a stationary frame or support attached to the body portion *b* of the road vehicle.

70 75 80 85 90 95 100 In the present instance, the stationary frame comprises a split hub 36 having arms 37, which are riveted or otherwise fastened to the body portion *b* of the vehicle, and said split hub receives the bushing or sleeve 35, which is clamped between the members of the split hub, by a bolt 38 extended through suitable ears 39 on the members of said hub. The arms 20, 21, of the mast supporting frame are keyed or otherwise fastened to the shaft 34 so as to rotate therewith, and said shaft is provided with a worm gear 40, which may be driven as herein represented by an auxiliary engine or motor 41 supported by the body portion *b* of the vehicle or said shaft may be otherwise rotated. The rotatable shaft 34 is confined against longitudinal movement by collars 42, 43, fast thereon.

105 110 115 120 125 In the present instance the worm 40 is driven by a worm 44 on a shaft 45 (see Figs. 1 and 14) provided with a pulley 46, which is connected by a belt 47 with a pulley 48 on the shaft 49 of the engine or motor 41, which latter is of the reversible type.

130 The boom 10 carries a bucket or scoop 50, which may be closed at its bottom, back and sides and open at its front end and provided with suitable teeth 51, and said bucket may be stationary or movable with relation to the boom, and may be arranged on the latter so that its front end is presented toward the front end of the boom or toward the rear end thereof, according to the kind of work to be performed. In Fig. 1, the bucket 50 is arranged with its open end toward the front end of the boom, and is movable longitudinally thereon, and when so arranged, the apparatus is adapted for work on or above the surface, the bucket being loaded on its forward movement from the rear of the boom toward the front thereof.

135 The forward movement of the bucket is effected by a cable or like device 52, which has one end fastened to the bucket and is passed over a guide roller 53 carried by the

boom in front thereof and under a guide roller 54 carried by the mast 19, and wound upon a drum 55 (see Figs. 9 and 10) supported by the body portion *b* of the vehicle 5 near the front thereof.

The bucket is guided in its movement lengthwise of the boom by suitable means, herein shown as arms 56 attached to the opposite sides of the bucket and extended upwardly on opposite sides of the boom, said arms being connected by a rod 57, which is designed to engage the under side of the boom and keep the bottom of the bucket parallel with the boom.

Provision is also made for automatically locking the bucket in its dumping position, while permitting the bucket to move lengthwise of the boom and also to move into its dumping position.

In the present instance, I have shown one form or construction of automatic lock, (see Figs. 1 and 13), which consists of elliptical blocks or cams 59 fast on arms 60 fastened to the opposite sides of the bucket, said cams 25 being located in sockets of corresponding shape and each of which is formed by recesses 61, 62, in bars 63, 64 forming trucks, which are located in each side channel or guideway 65 in the boom 10.

The bars 63, 64, are provided with rollers 66, which are designed to engage the top and bottom flanges of each guideway or channel 65 in the boom, and said rollers are designed to be pressed in sufficiently firm engagement with the said flanges to hold the trucks stationary, by the cams 59 forcing apart the members or bars 63, 64, of the truck, when the bucket is turned into its dumping position.

One of the bars as 63 may be provided with end pieces 68 which serve as guides for the other bar or member 64.

In the arrangement shown in Fig. 1, the bucket is dumped by slackening away on the cable 52 with the boom 10 in its elevated position. When the cable 52 is slackened, the weight of the bucket and its load, causes the bucket to turn from a position substantially parallel with the boom into one at an angle thereto, in which the open front end of the bucket is pointing downward and the bottom of the bucket is in a substantially vertical plane. When the bucket is in its dumping position just described, the cams 59 are in a position substantially at right angles to that shown in Figs. 1 and 13 and the trucks 63, 64, are rendered stationary on the boom, and when the bucket has been dumped, it is returned to its working or operative position with its bottom substantially parallel with the boom, by taking up the slack in the cable 52, which automatically unlocks the trucks and leaves the bucket free to travel lengthwise of the boom 65 and be returned to its starting position at

the rear end of the boom by gravity, the hauling cable 52 being unwound while kept under sufficient tension to maintain the bucket substantially parallel with the boom in order to permit this return movement of the bucket.

With the arrangement shown in Fig. 1, the boom 10 is elevated by a hoisting cable 70, which has one end fastened to the mast 19 at 71 and is passed under a sheave 72 carried by arms 73 extended from the carriage 15, and said cable is then passed over a sheave 74 carried by the mast 19, and is wound upon a drum 75 mounted on the same shaft 76 as the drum 55.

The winding drums 55, 75, are normally loose on the shaft 76 and are adapted to be rendered fast thereon by clutches 78, 79, of any suitable construction and which are controlled as herein represented by suitable levers 80, 81, (see Fig. 10). The winding drums 55, 75 may be held stationary by band brakes 82, 83, controlled by levers 84, 85, in a manner well understood.

The drum shaft 76 is operatively connected with the motor or engine *e* employed to propel the vehicle, which may be effected in any suitable manner, as for instance, as shown in Figs. 1, 9, 10, 11, wherein the drum shaft 76 is shown as provided with gears 86, which mesh with pinions 87 on a countershaft 88, which is driven from a shaft 89 by a belt 90. The shaft 89 constitutes the crank shaft of the engine *e*, which is connected by a transmission with gears 91 on the rear wheels *c* 100 of the vehicle.

The transmission herein shown comprises a shaft 92 having a gear 93 which meshes with a gear 94 on the crank shaft 89, and is provided with gears 95, 96, with which co-operate gears 97, 98 on a shaft 99 having pinions 100 which mesh with the gears 91 on the rear wheels *c*.

The gears 97, 98, are capable of being moved on the shaft 99 from their neutral position, shown in Fig. 11, in one direction to engage the gears 97, 95, and cause the engine or motor to propel the road vehicle *a* at one speed, and the gears 97, 98 are moved in the opposite direction to engage the gears 98, 96, and cause the engine or motor to propel the vehicle at a different speed.

When the gears 97, 98 are in their neutral position shown in Fig. 11, they are out of mesh with the gears 95, 96, and the vehicle is at rest while the engine continues to run.

The shaft 92 is driven from the crankshaft 89 by the gears 94, 93, and the shaft 92 is geared to the shaft 99 by the gears 101, 102, the latter being normally loose on the shaft 99 and adapted to be rendered fast thereon by a clutch of any suitable construction, which is conventionally represented as a member 103 fast to the gear 102 and a mem- 130

ber 104 mounted on the shaft 99 to rotate therewith and to slide thereon. The clutch member 104 may be moved by a shipper or clutch rod 105 or in any other suitable manner. By means of the clutch 103, 104, the vehicle *a* may be propelled without necessitating stopping of the engine to shift the gears 97, 98. The crankshaft 89 is provided with a pulley 106, which is normally loose thereon and adapted to be rendered fast to said shaft by a clutch member 107 coöperating with a clutch member 108. The pulley 106 is connected by the belt 90 with a pulley 109 on the shaft 88.

With the arrangement shown in Fig. 1, the bucket 50 may be moved from the rear to the front of the boom 10 so as to pick up its load from the surface of the road, by throwing in the clutch member 107 so as to rotate the drum shaft 76, and by operating the clutch lever 80 so as to render the winding drum 55 fast on its shaft 76 and effect winding of the cable 52 upon the drum 55. When the bucket has been loaded, the drum 55 is held by the brake band 82, and the clutch lever 81 is operated to wind up the cable 70 and elevate the boom, as for instance, into the position shown in Fig. 2.

When the bucket has been elevated, the shaft 34 is rotated so as to move the mast supporting frame to the right or left and thereby bring the loaded bucket into the desired position for dumping.

The movement of the shaft 34 is effected by manipulating the reversible engine 41 according to whether the bucket is to discharge its load on the right or left side of the tractor or vehicle *a*.

To dump the load in the bucket, it is only necessary for the operator to release the brake 82 on the drum 55 and allow the cable 52 to be paid out, which permits the bucket to turn on the cams 59 as a pivot and assume a substantially vertical position over the receptacle into which it is desired to discharge the load. When the bucket is in its dumping position, it is automatically locked on the boom and prevented from running down thereon, by the action of the cams 59 as above explained.

After the bucket has discharged its load, the drum 55 is rendered fast on its shaft 76 to take up the slack in the cable 52 and bring the bucket back into its operative position substantially parallel with the boom.

The apparatus as represented in Fig. 1 is adapted for excavating or surface work, but the construction is such, that the apparatus may be converted in a minimum time into an apparatus for other kinds of work as will now be described.

In Figs. 3 and 4, I have shown the apparatus as arranged for trench work, for which purpose, the bucket 50 shown in Fig.

1 is used but is reversed on the boom, that is, its front or cutting edge is arranged to move toward the mast 19 when taking its load, and the rear end of the bucket is connected by a cable, rope or the like 110 with the carriage 15, which is made movable on the track 14 by removing the fastening pin 16. In this case, the bucket is located near the outer end of the boom when in its starting position and is moved toward the rear end of said boom when taking its load.

The bucket 50 is moved so as to take its load by winding the cable 52 on the drum 55, which cable in this case is attached to the front of the bucket, and on this movement of the bucket, the carriage 15 is moved on the track 14 toward the front end of the boom, the cable 70 being paid out to permit of this movement of the carriage. When the bucket is loaded, the cable 70 is wound up on its drum 75 until the carriage 15 meets a stop or block 112 which is fastened to the track 14. The loaded bucket is thus brought back to near the front end of the boom, which is then lifted by winding up the cable 70 until the bucket has been removed from the trench, whereupon the shaft 34 is rotated so as to bring the bucket into dumping position, whereupon the cable 70 is held and the cable 52 slackened to permit the bucket to be turned by gravity into its dumping position, in which it is automatically locked as described with reference to Fig. 1.

When used in trench work, the pivot carrier 18 for the boom is moved up on the mast 19 by a hand line 113 and is secured in its adjusted position thereon by means of bolts or screws 130 or otherwise, and by adjusting said member on said mast, the boom may be given different angular positions, according to the angle on which it is desired the bucket should cut.

In Fig. 4, the pivot carrier 18 is shown as adjusted on the mast 19 with the latter in its vertical position, and the boom is capable of being lowered into a trench to have the bucket cut the earth at one angle, and by raising or lowering the pivot carrier 18 on the mast 19, the angular position of the boom with relation to the mast may be changed to vary the cut made by the bucket. It is also highly desirable to be able to make a substantially vertical cut in the trench, as for instance, to form an end wall therein, and for this purpose, the mast 19 is made adjustable from a substantially vertical position into different angular positions, which is accomplished as herein shown by providing the mast supporting frame with the extension 24. When the mast 19 has its free or upper end secured in fixed relation to the extension 24, as for instance, as represented in Fig. 3, it will be seen that

the boom 10 assumes a substantially vertical position, and that the bucket when moved upward will make a substantially vertical cut. The features of the pivot carrier 18 for the boom being adjustable on the mast, and the latter capable of adjustment into an inclined position, may be advantageously employed with a bucket which does not travel lengthwise of the boom, but is located near the front end thereof, as represented in Fig. 5, and is capable of being moved in the arc of a circle with the pivotal attachment 115 of the bucket to the boom as a center.

When the parts are arranged as shown in Fig. 5, the bucket makes a circular cut, and may be advantageously used for side hill or trench cutting and in other places where crowded motion is required, which latter is obtained by moving the vehicle forward.

The feature of the pivot carrier 18 for the boom being adjustable lengthwise of the mast, enables the apparatus to be used for other purposes than digging or cutting work, and further permits other forms of buckets to be used for different purposes.

This is illustrated by Figs. 6, 7 and 8. In Fig. 6, the pivot carrier 18 is located at the bottom of the mast, and the bucket 50 is of the ordinary kind for holding materials.

The arrangement shown in Fig. 6 can be used to advantage for handling materials employed in making concrete, such as the aggregate, for in this case the boom can be manipulated so as to place the bucket above the pile of aggregate and then lowered to the ground to be filled, after which the loaded bucket is raised and the boom swung around to the concrete mixer, into which the load in the bucket may be dumped.

In this manner, the materials may be handled with a minimum expense, time and labor.

In Fig. 7, the pivot carrier 18 is adjusted into an elevated position and the boom is raised into a horizontal position, and the bucket 50 used is shown as of the clam-shell type, which can be loaded and unloaded by manipulating the friction drums 55, 75, and 50 which can be swung from its loading position into its unloading position, etc. With the apparatus adjusted as shown in Fig. 7, a different tool or device other than a bucket may be used for hoisting other objects, similar to a derrick.

In Fig. 8, the pivot carrier 18 is shown as adjusted into a different position on the mast from that shown in Figs. 6 or 7, and a different type of bucket used, which is movable lengthwise on the boom and into which aggregate or other material can be shoveled when the bucket is near the rear of the boom and then moved to the front end of the boom, and swung around until it is over

the hopper of the concrete mixer, and then dumped.

It will be understood, that the mast, boom, etc., shown in Figs. 6, 7 and 8, are used on the tractor or road vehicle shown in Fig. 1, and are shown to illustrate the scope and usefulness of a tractor, road roller or like vehicle embodying this invention.

By reference to Fig. 1, it will be observed that the mast is not rotated on its own axis but is carried by a frame which rotates with a shaft supported by a frame or device fastened directly to the body portion of the vehicle, and as a result, the end thrust is transmitted to and is taken care of by the body portion of the vehicle, which is of sufficient strength to do so.

I have herein illustrated one form of road vehicle, but it is not desired to limit the invention in this respect.

Claims:

1. In a vehicle of the character described, in combination, a motor propelled vehicle, a vertically arranged frame projecting in front of said vehicle and pivoted thereto to turn laterally with relation to said vehicle and extended above and below said pivot, a vertically arranged mast carried by said frame, a boom carrier movable longitudinally on said mast, a boom pivoted to said carrier to move vertically, a bucket movable lengthwise on said boom, winding drums supported by said vehicle independently of said frame, and flexible connections between said boom and bucket and said winding drums.

2. In a vehicle of the character described, in combination, a motor propelled vehicle, a supporting frame attached to said vehicle, a mast carried by said frame, a boom supported by said mast and pivoted to move vertically, a track on said boom extended in the direction of the length thereof, a carriage capable of being moved on said track, a bucket carried by and movable on said boom and connected with said carriage to move on the boom in opposite directions to the said carriage, and means on the vehicle for elevating the free end of the boom, said means being connected with said carriage.

3. In a vehicle of the character described, in combination, a motor propelled vehicle, a boom carried by said vehicle and pivoted to move vertically, a carriage mounted on said boom between the ends thereof and capable of being moved lengthwise thereof, and means on said vehicle for elevating the free end of said boom, said means being connected with said carriage.

4. In a vehicle of the character described, in combination, a motor propelled vehicle, a boom carried by said vehicle and pivoted to move vertically, a carriage mounted on said boom between the ends thereof and ca-

pable of being moved lengthwise thereof, means for rendering said carriage stationary on said boom, and means on said vehicle connected with said carriage for elevating the 5 boom.

5. In a vehicle of the character described, in combination, a motor propelled vehicle, a shaft rotatable in a support affixed to the body portion of said vehicle, a supporting 10 frame fixed to said shaft to rotate therewith and provided at its upper end with a curved extension, a mast pivoted at its lower end to said frame and having its upper end capable of being moved about the said pivot as 15 a center to permit the mast to be moved from a vertical into an inclined position, means for securing the upper end of the mast to said curved extension in fixed relation thereto, a boom carrier movable lengthwise on said mast, and a boom pivoted to 20 said carrier.

6. In a vehicle of the character described, in combination, a motor propelled vehicle, a mast carried thereby, a boom carrier movable 25 lengthwise on said mast, a boom pivoted to said carrier, a carriage capable of being moved lengthwise of said boom, means for rendering said carriage stationary on said boom, and means connected with said 30 carriage for elevating said boom.

7. In a vehicle of the character described, in combination, a motor propelled vehicle, a boom carried thereby and pivoted to move vertically, a carriage mounted on said boom 35 between the ends thereof and movable on said boom lengthwise thereof, means for rendering said carriage stationary on said boom, and means attached to said carriage for elevating the free end of said boom.

8. In a vehicle of the character described, in combination, a motor propelled vehicle, a boom carried thereby, a bucket movable on 40 said boom in the direction of the length of the same and substantially parallel therewith, and pivotally mounted to turn away 45 from the boom into dumping position, means

for moving said bucket lengthwise of the boom, means for maintaining the bucket substantially parallel with the boom as it is moved forward lengthwise of said boom, 50 and means actuated by movement of the bucket into its dumping position for automatically locking said bucket in fixed position on said boom when the bucket is moved into its dumping position and for unlocking said bucket when the latter is moved into its operative position.

9. In a vehicle of the character described, in combination, a motor propelled vehicle, a supporting frame carried by the vehicle 60 and projecting in front thereof and pivoted thereto to turn laterally and extended above and below the pivot therefor, an upright mast carried by said frame, a boom carrier movable lengthwise of said mast, a boom 65 pivoted to said carrier to move vertically, a bucket movable on said boom lengthwise thereof, and winding drums supported by said vehicle at the rear of said frame and independently thereof and operatively connected 70 with said bucket and boom and with the motor of said vehicle.

10. In a vehicle of the character described, in combination, a motor propelled vehicle, a vertically arranged rotatable shaft mounted 75 in front of said vehicle, a supporting frame mounted on said shaft to rotate therewith and projecting in front of said vehicle and extended above and below said shaft, a mast carried by said frame in fixed relation 80 thereto, a boom carrier movable lengthwise of said mast, a boom pivoted to said carrier to move vertically, a bucket movable on said boom, and winding drums supported by said vehicle at the rear of said frame and independently thereof and operatively connected 85 with said bucket and boom and with the motor of said vehicle.

In testimony whereof, I have signed my name to this specification.

FRANK B. MCGRANE.

Copies of this patent may be obtained for five cents each, by addressing the "Commissioner of Patents, Washington, D. C."
